UNITED STATES PATENT OFFICE.

JAMES F. EDWARDS, OF WASHINGTON, DISTRICT OF COLUMBIA.

ANGLE-BRICK AND MOLD.

SPECIFICATION forming part of Letters Patent No. 252,747, dated January 24, 1882.

Application filed November 22, 1881. (Modul.)

To all whom it may concern:

Be it known that I, JAMES F. EDWARDS, of Washington city, District of Columbia, have invented a new and Improved Angle-Brick and 5 Mold; and I do hereby declare that the following is a full, clear, and exact description of the same, reference being had to the accompanying drawings, forming part of this specification, in which—

10 Figure 1 is a ground plan of a bay-window. Fig. 2 is a top view of my brick enlarged. Fig. 3 is a top view of the mold, showing in dotted lines the variations in the angle. Fig. 4 is an enlarged view in detail, showing the rule-joint at the adjustable angle. Fig. 5 is an end view 15 of the mold, partly in section through the line xx of Fig. 3, looking in the direction of the arrow. Fig. 6 is a perspective view of the front pier of the bay-window beneath which it is 20 placed, illustrating the old method of laying the brick; and Fig. 7 is a perspective view of the front pier of the bay-window beneath which it is placed, illustrating the manner of laying my brick.

25 The object of my invention is to provide an angle-brick for bay-windows and other obtuse-angled-wall structures in which the bricks at the angle shall be substantially tied with lap-joints, and in which all cutting of brick shall 30 be avoided, while the angle may be changed as desired.

In the ordinary methods of forming angled-walled structures, when the angle is greater than a right angle, a number of objections exist. 35 One method is to run up the wall or piers with the vertical joints coinciding at or near the angle, which is very objectionable for the reason that it is an insecure mechanical structure, there being nothing to tie the two walls forming the faces of the angle together, which involves a liability to crack and fall apart. The other method is to place in the rectangular brick-mold triangular blocks, which make one edge of the brick angled or wedge-shaped. This 40 permits the tie or lap to be made at the angle; but as the longitudinal sides of these angled bricks are of less length than the sides of a full-sized brick, it necessitates, when they are being laid, the supplementing of the deficient 45 length by the workman by what is known as "closures" and "three-quarter bats." These

are in fact only parts of bricks, which have to be cut by the hammer and placed in as the work progresses. This latter method, it will be seen, involves an expenditure of much time 55 and labor, and the edges of these cut sections of brick cannot always be cut smoothly, so as to make an even and straight finish at the mortar-joint.

In overcoming all of these objections my invention consists in a brick which is formed with one end rectangular and the other end wedge-shaped, which brick is so proportioned that the shorter of the two longitudinal edges is just equal to the normal length of a full brick, while 65 one of its beveled ends is exactly equal to the end of a full brick, or one-half of the length of a full brick.

The invention also consists in a mold for forming this brick which is made adjustable, so 70 as to regulate the size of the angle at the two exposed edges of the brick, as hereinafter more fully described.

In the drawings, A represents my improved brick, which, so far as the general outline of 75 its five sides is concerned, does not vary from the angle bricks heretofore used. Its peculiarity, however, consists in making the shorter one, a , of its two longitudinal edges exactly equal to the normal length of a full-sized brick, 80 and with the beveled face b , which slopes to this angle, exactly equal to the end of a full brick, or half the length of a full brick.

Now, in describing more clearly the great merit which my brick has in the construction 85 of angled-walled structures when the angle is greater than a right angle, I refer to Figs. 1, 6, and 7, which represent, partly in ground plan and partly in perspective, a bay-window in process of construction.

At $B B' B^2$ are piers constructed with my brick, while at C is a pier constructed according to the method in general use, in which closures and three-quarter bats are employed. Now, at C , which shows the old method, it 95 will be seen that the angle-brick $A B$ having its sides much shorter than the length of a brick, an end section or half-brick is not long enough to fill out the side of a fourteen-inch pier, while a whole brick is too long, and therefore a three-quarter bat, $\frac{3}{4} B$, has to be cut to fill out this side of the angle, while its

bevel face being less than half a brick, a full brick, F B, is not long enough to fill out the other side of the pier, and a piece, *c*, called a "closure" has to be put onto the end of the same. This method of cutting and fitting has to be practiced at every layer of brick, and it not only involves much time and trouble, but the vertical joints do not occur regularly in the middle of the bricks above and below it, and the finish is unsymmetrical, while the chiseled edges of the cut sections will not make as straight a joint as can be desired.

In my invention, as shown at B, it will be seen that the side *a* of my brick and the end 15 of a full brick on one side of the angle are exactly equal to the face *b* of my brick and the side of a full-sized brick on the other side of the angle in all of the layers, and the result is that at the angle I get the benefit of the lap of 20 a half-brick's length, which ties the two walls together. All cutting of closures and three-quarter bats is avoided, thereby saving much time and trouble. The vertical mortar-joints occur at the middle of the brick above and 25 below, making a symmetrical finish, and no ragged edges of brick exist.

I have so far described my brick in the construction of a fourteen inch pier, one-half inch being always allowed for the mortar-joint. It 30 is obvious that my invention is also applicable to nine-inch piers, or piers of any other width which are equally divisible by the length of a brick or a brick and a half, and I may use it not only in the construction of bay-windows, 35 but also in the angles of buildings, or wherever it may be applicable.

For making my brick and giving it a variable angle at the point between the faces *a* and *b* which forms the angle in the wall, I construct 40 a mold, D, with five sides, open at top and bottom, of which the side *a'*, which forms the side *a* of the brick, and the side *b'*, which forms the side *b* of the brick, are adjustably jointed together with rounded and concaved edges and 45 rule-joint hinges *d*, so that a perfect angle will be formed at this point for all different adjustments of the part *b'*. For holding the part *b'* to its position it is connected to the beveled piece *c'* of the mold by a set-screw or other 50 equivalent device; and suitable slots and guides may be provided, as shown in Fig. 5, which slots are preferably covered by a follower to

prevent the clay from working through. As the side *a'* is always equal to the length of a full brick and the side *b'* always equal to the width of a full brick, it matters not what angle these two sides *a'* and *b'* are set at, the brick will be perfect in its fitting, and it is not even necessary that the wall of the mold opposite *a'* shall be exactly parallel with it, for all the 60 sides of the brick are next to mortar-joints except *a* and *b*.

Having thus described my invention, what I claim as new is—

1. An angle-brick having one of its longitudinal faces equal in length to that of a normal brick, and having a bevel face inclining at an obtuse angle from the plane of said longitudinal face and equal in extent to the width of a normal brick, substantially as and for the purpose described. 65

2. An obtuse-angled-wall structure composed of rectangular bricks of a normal or definite length and angle-bricks, each of the latter having one of its longitudinal faces equal in length 70 to that of a normal brick, and having a bevel face inclining at an obtuse angle from the plane of said longitudinal face, which bevel face is equal in extent to the width of a full brick, substantially as and for the purpose described. 80

3. An angle-brick mold constructed substantially as described, and having the inner wall of its side *a'* equal to the length of a full brick and its side *b'* equal to the width of a full brick, and having also these two sides jointed together 85 for forming a variable angle, as described.

4. An angle-brick mold having its two sides which form the exposed faces of the brick connected together by an adjustable joint for varying said angle, as described. 90

5. An angle-brick mold having its two sides which form the exposed faces of the brick connected by a rule-joint with concave and convex edges, as described.

6. An angle-brick mold having its two sides 95 which form the exposed faces of the brick connected by an adjustable joint, and a set-screw for fixing the position of the adjustable section, as described.
